UNITED STATES PATENT OFFICE

2,510,460

AUTOMATIC STARTER SWITCH

Albert Brooke and William Naumann,
Staten Island, N. Y.

Application January 8, 1948, Serial No. 1,138

2 Claims. (Cl. 200—83)

1

This invention relates to improvements in automatic starters for internal combustion engines.

An object of the invention is to provide an improved automatic starter for an internal combustion engine which will be operated by the turning on of the ignition switch, and which will be automatically stopped when the internal combustion engine begins its operation.

Another object of the invention is to provide an improved automatic starter for internal combustion engines which will be set into operation by the turning on of the ignition switch to close an electric circuit including the starter motor, a solenoid switch, an oil pressure switch, the usual high tension coil and distributor.

A further object of the invention is to provide an improved automatic starter for internal combustion engines which will be set into operation by the turning on of the ignition switch to close an electric circuit including the starter motor, a solenoid switch, an oil pressure switch, the usual high tension coil and distributor, said oil pressure switch automatically breaking the electric circuit when the internal combustion engine has started and has built up oil pressure in the oil line to the engine bearings.

A still further object of the invention is to provide an improved oil pressure switch controlled automatic starter for internal combustion engines which will be highly efficient in operation and relatively inexpensive to manufacture and produce.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawings:

Figure 1 is a side elevation of the improved oil pressure switch with a part of its housing being broken away to show the interior construction thereof, and connected with the other essential parts of the automatic starter, with the oil pressure switch shown in closed position.

Figure 2 is a plan sectional view taken on line 2—2 of Figure 1.

Figure 3 is a similar view to that shown in Figure 1, but with the oil pressure switch shown in open position.

Figure 4 is a diagrammatic view of the wiring circuits used with the automatic starter.

2

Like characters of reference are used throughout the following specification and the accompanying drawings to designate corresponding parts.

5 In carrying out the invention, there is provided an improved form of oil pressure switch including an outer housing or casing having an upper portion 1 formed with a laterally extending flange 2 about its lower end, and a cooperating lower portion 3 formed with a laterally extending flange 4 about its upper end.

A contact holder 5 of insulated material is supported between the flanges 2 and 4, and supports the diametrically opposed contacts 6 and 7, secured thereto by means of the screws 8. The holder 5 is centrally apertured as at 9 to permit the vertical movement of the switch actuating push rod 10, hereinafter more fully described.

The oil pipe line 11 is connected axially through 20 the lower portion 3 of the oil pressure switch casing by means of the nut 12 which threads on to the lower end of the flanged fitting 13 which supports the bellows 14 disposed in the said lower portion 3 of the switch casing. A socket 15 is 25 formed in the upper end of the fitting 13 and supports the lower end of the push rod 10 which is formed with an annular flange 16 adjacent its upper end.

A contact washer 17 having oppositely disposed 30 depending contacts 18 and 19 is provided, and is centrally apertured to receive the upper end of the switch actuating push rod 10, the flange 16 extending in contact with the lower surface of the washer 17 for supporting the same.

35 Vertically spaced insulated bushings 20 and 21 are separated by a coil spring 22, the same being vertically and adjustably supported in a depending tubular collar 23 formed on the top of the upper portion 1 of the switch casing. A set adjusting screw 24 is threaded into the upper end of the collar 23 in contact with the bushing 20 for selectively varying the operating tension of the switch.

The oil pipe line 11 will be connected with the 45 oil pump (not shown) driven by the internal combustion engine (also not shown), and the contact 7 will be connected by the conductor 25 with the ignition switch 26, and with the usual high tension coil 27 which will be connected to the distributor 28 and grounded at 29.

The other side of the ignition switch 26 will be connected by the conductor 30 to a solenoid switch 31, and from thence will connect with the contact 6 by means of the conductor 32. The other side 55 of the solenoid switch 31 will be connected by the

conductor 33 to the starter motor 34, which in turn will be connected to the ground 35. The conductor 30 will be connected to one side of the storage battery 36, and the other side of the battery will connect with the ground 37.

In operation, the ignition switch 26 will be closed and the circuit including the battery 36, solenoid switch 31, and starter motor 34 will be closed and the internal combustion engine (not shown) will be turned over by the starter motor 34. As soon as the internal combustion engine starts to run, the pressure of the oil will be built up in the line 11 and in the bellows 14 to raise the actuating push rod 10 upwardly, thereby separating the contacts 18 and 19 from the contacts 6 and 7, thence turning off or stopping the starter motor 34. Should the internal combustion stop while the ignition switch 26 was closed, the oil pressure would drop, thence again closing the contacts 18 and 19 with the contacts 6 and 7 to again crank the engine.

While the preferred embodiment of the instant invention has been illustrated and described, it will be understood that it is not intended to limit the scope of the invention thereto, as many minor changes in detail of construction may be resorted to without departure from the spirit of the invention.

What is claimed is:

1. In a fluid pressure switch, a body portion, a contact holder supported within the body portion, said contact holder having a central opening, contacts mounted on the contact holder, a fluid pipe extending into the body portion, spaced bellows supported on the fluid pipe within the body portion and forming a part thereof, into which fluid under pressure passes from the pipe, a socket member secured to the uppermost bellows, movable into the central opening of the contact holder as the bellows expands under the action of fluid entering the bellows, a vertically movable contact washer mounted above the contact holder, contacts on the washer cooperating with the contacts on the holder completing an electrical circuit, a push rod resting on the socket member engaging the contact holder, elevating the contact holder, disengaging the contacts and breaking the electric circuit when the socket member is elevated, and regulating means for regulating the initial position of the contact washer with respect to the 50

5 contacts on the contact holder, said regulating means including a tubular collar, an insulated bushing extending into the collar and resting on the contact washer, and a coiled spring mounted in the collar normally urging the bushing into contact with said contact washer.

2. In a fluid pressure switch, a body portion, a contact holder supported within the body portion intermediate the ends thereof, the contact holder 10 being disposed in a horizontal plane, said contact holder having a central opening, contacts mounted on the contact holder, a fluid pipe including superposed bellows, extending into the body portion, a guide member secured to the uppermost bellows and being movable through the central opening of the contact holder, a vertically movable contact supporting washer mounted above the contact holder and having contacts engageable with the contacts of the contact holder in completing a circuit, a push rod engaging said guiding member and being in contact with the washer, whereby said washer is elevated by the pressure of fluid in the bellows, breaking the circuit between the contacts of the contact holder and washer, a tubular collar forming a part of the body portion, an insulated bushing extending into the collar and resting on the washer, adjustable spring means within the tubular collar forcing the insulated bushing downwardly regulating the normal position of the movable washer and contacts supported thereby.

ALBERT BROOKE.
WILLIAM NAUMANN.
